(57) **CLAIM**

The ornamental design for a spoon, as shown and described.

DESCRIPTION

FIG. 1 is an isometric view of a spoon according to the present application;

FIG. 2 is a top view of the spoon;

FIG. 3 is a bottom view of the spoon;

FIG. 4 is a side view of the spoon;

FIG. 5 is a front view of the spoon; and,

FIG. 6 is a rear view of the spoon.

The broken lines show portions of a spoon and form no part of the claimed design.
